ELECTRIC ROBOT PHONOGRAPH

Lloyd J. Andres, Chicago, Ill., and Gilbert A. Magruder, Grand Rapids, Mich., assignors to Automatic Instrument Company, a corporation of Michigan

Application May 18, 1936, Serial No. 80,360

20 Claims. (Cl. 274—1)

This invention relates in general to a multiple circuit closer for use in such devices as robot phonographs, sign flashers, and the like, for electrically initiating various visual and aural effects at predetermined time intervals corresponding to recorded sound sequences.

In a talking robot machine, a phonograph is used for providing the speech and the electric actuation of various devices are caused by control circuits connected to a switch mechanism which successively makes a very large number of circuit closing contacts in each cycle of its operation so that various devices may be operated substantially at any desired intervals and in synchronism with the talking record. A combined mechanism of this kind is now generally known, accepted and designated as a robot phonograph or "robophone".

An important object of the invention is in the provision of an automatic mechanism and associated electrically actuated equipment wherein a number of displays may be animated and visual effects produced in synchronism with special or sound recordings previously made.

A further object of the invention is in the provision of a comparatively simple mechanism for providing a mechanically driven switch closing device which is positive and reliable in operation requiring very little fixed internal wiring, sole-noids, or other electrical parts; and to provide a mechanism which is automatically restored to normal starting condition.

Other objects and advantages will appear hereinafter, the drawings illustrating a preferred embodiment of the invention which is shown in a partially diagrammatic manner. In the drawings,

Figure 1 is a somewhat diagrammatic representation of a display including various electro-mechanical devices in connection with a repeating phonograph; and

Figure 2 is a wiring diagram for a portion of the mechanism shown in Figure 1.

In the operation of a robot phonograph the records are designed to operate at approximately thirty-three and one-third revolutions per minute and each record plays from ten to fifteen minutes. If three electrical contacts are made for each revolution of the record, the apparatus provides a series of electrical impulses spaced approximately three-fifths of a second apart. Thus about one hundred contacts are made each minute and a total of ten to fifteen hundred contacts for long records. This mechanism is particularly designed for repeating visual and

aural effects such as a display where a lecture or talk is supplemented by operation of various parts at predetermined timed intervals, and after being set for any display, it is intended to repeat automatically in proper timed relation without further attention thereto. Although the disc type of sound records are used, the apparatus will operate equally well with a repeater mechanism to reproduce photographic recordings on film, or magnetic recordings on wire.

Referring now more particularly to the drawings, an example of the principal component parts is shown diagrammatically in Fig. 1 and in an actual installation these parts are all combined in a single portable case having a single power cord which may be plugged into a convenient source of electrical power. A phonograph or record repeater mechanism 20 comprises a driving motor 21 receiving current from a suitable source of power for operating a turntable 22 for carrying a disc record 23 centered by a turntable shaft 24. A tone arm 25 is mounted to engage a pickup needle 26 with the grooves of the record and sound currents are transmitted through conductors 27 to an amplifier 28 and thence are transmitted by conductors 29 and 30 to loud speakers 31.

A rotary timing switch 32 and locking relays 33 are connected with each other by a cable 34 and the rotary timing switch is connected to the motor 21 by a cable 35 and with a timing panel 36 by a cable 37. These cables contain a number of electrical conductors for making the necessary circuit connections between the parts. For a large number of loud speakers a similar loud speaker cable 38 may be connected from the locking relays to the timing panel 36.

In the timing panel are a number of plug-in openings 40 designated as external connections for power, 41 for sound, 42 for a short impulse circuit, and 43 for common circuits. Corresponding to the power and sound plugs are on and off plug connections 44 and 45 respectively.

For electrically connecting these plug openings are a number of jumpers or circuit connectors 46 which may be inserted at their ends into any of the plugs for making the necessary circuit connections in proper timed relation with the sound record.

Also connected to the external connection plugs 40 are a number of electrical operating devices which receive their power from electric supply mains 50 and 51 and may comprise any number of different devices represented in Fig. 1 as an electric lamp 52 having conductors 53 and 54 joined

to the current supply means; a bell 55 having conductors 56 and 57 connected to the supply means, a motor 58 having conductors 59 and 60 to the supply means, an electro-magnetic switch 61 having conductors 62 and 63 to the supply means, and such other additional, similar, or different devices electrically operated and connected in a similar way.

Extending from the rotary timing switch is an electromagnetic counter 64 connected to the timing switch by conductors 65 and having an opening 66 for exhibiting numbers in accordance with the electrical contacts or impulses which are made by the phonograph 20. This counter is used by an operator to determine the position of the desired excited circuit which is to be related by the timing panel, to the recorded sound.

As shown mechanically in Fig. 2 and diagrammatically in Fig. 1, the record repeater or phonograph is provided with three mechanically operated switches. One of these switches comprises a cam 70 secured to and rotatable with the turntable shaft 24 and preferably having three angular projections or lobes to engage a movable contact member 71 for momentarily completing an electric circuit with its relatively fixed contact 72. The number of contacts per rotation may be changed to suit different conditions by simply changing the cam 70 but three contacts per rotation are found satisfactory in practice.

The second switch comprises an insulated thimble 73 carried by an arm 74 integral or directly movable with the tone arm 25 and arranged to slip between spring contact makers 75 and 76 to break contact between them and to close an electrical connection as soon as the tone arm is in proper position to engage the starting groove of the record.

The third switch comprises a cam 77 mounted upon a shaft 78 or integral with a cam for operating the tone arm 25 designed to complete one rotation for each complete cycle of the tone arm. This cam has a flat side 79 engageable with a central spring contact arm 80 for making connection in rest position with a contact arm 81 and when raised from the rest position with a contact arm 82. In the rest position the contacts 80 and 81 complete a rotary switch reset circuit to be described later. When the tone arm reaches its start or play position the contacts 80 and 81 are opened and the contacts 80 and 82 are closed.

A battery 83 or a similar source of power is connected through one pole 84 of a manually operable two-pole switch by means of a conductor 85 to the central contact 80. Conductors 82 and 76 of the switches are connected by a conductor 86, arms 75 and 72 are connected by a conductor 87 so that the three switches are connected in series. The other arm 71 of the timing switch is connected by a conductor 88 to a magnet winding 89 and thence through a conductor 90 to the other side of a battery 83. The other pole 84^a of the two-pole switch closes a connection for conductors 50 for the power circuit to the various operative devices. This dual or two-pole switch 84-84^a is manually operated and controls both the power source for operating the timing apparatus and the record repeater or phonograph.

The timing circuits are completed by special electromagnetic rotary switches of which two or more separate switches are utilized to accomplish the desired results. The use of two 50-segment 75 rotary timing switches provides 2401 (49×49)

possible circuit changes during one cycle of operation. This number of possible circuit changes is more than enough unless records of more than twenty minutes duration are used, which would require an additional rotary switch. In Fig. 2, two separate switches 93 and 94 are represented, the first having two electrically independent circular sets of contact segments 95 and 96 and two electrically independent brushes 97 and 98 therefor, respectively. The brushes 97 and 98 are rotatable with a shaft 99 and insulated from the shaft by insulation 100. A ratchet 101 is attached to the shaft 99 and actuated by a pawl 102 connected to a pivotally mounted armature 103 attracted by the magnet winding 89. When the magnet winding is energized the armature is drawn down against tension of a restoring spring 104 and the pawl 102 is moved down to engage the next tooth of the ratchet with which it is held in engagement by its spring 105. Each time the 10 solenoid 89 is energized the brushes 97 and 98 are therefore moved from one contact to the next succeeding contact, the actual movement being effected by the tension of the restoring spring 104 in drawing the armature 103 back against 15 its stop 106.

Also engaged by the armature 103 is a movable contact arm 107 for making an electrical connection with a relatively fixed contact arm 108 connected by a conductor 109 with the brush 97. The contacts 107 and 108 are separated when the armature 103 is attracted and as the movable contact 107 is electrically connected to the conductor 88 the energizing circuit is broken to the brush 97 until the armature is returned by its restoring spring at which time the brush 97 is moved to the next contact 95.

The second switch 94 has an exactly similar arrangement, contacts, brushes, shaft, and operating mechanism. Its magnet winding 89 however is connected at one terminal to the conductor 90 and at the other terminal to a conductor 110 which leads to one of the contacts 96 of switch mechanism 93, this conductor 110 being also connected to the movable contact arm 107 of the switch 94. The contact brushes 98 of the switches 93 and 94 are connected by conductors 111 with the opposite side of the battery 83 to which the conductor 90 is connected.

Each of the contacts 96 of the switch 93 is connected to timing jacks 112 having a plug-in terminal for each conductor, and each of the contacts 96 of the second switch 94 is connected to a timing jack 113 having corresponding plug-in connections.

At the top of Fig. 2 are shown a number of locking relays used to hold external circuits in closed position. Each of these relays comprises a pair of solenoids 120 and 121 having winding terminals 122 and 123, and 124 and 125 respectively. A double armature 126 is mounted intermediate its ends to be attracted by either one or the other of the solenoids. Above the armature are relatively fixed and movable contact arms 127 and 128 respectively, the lower one having a projection 129 adapted to be engaged by the armature 126 when one of the solenoids 121 is energized, thereby closing a circuit between the contact arms and the contact arms 127 and 128 being connected to switch terminals 131 and 132 respectively for energizing an external circuit for controlling a lamp, motor, bell, or any other electro-motive device. A number of plug-in connectors 133, 134, 135 and 136 are provided for operating each locking relay, each connector hav-

ing terminals for engaging the plug-in sockets and making an electrical connection therewith so that they can be quickly connected and disconnected. When a locking relay receives an impulse 5 energizing the armature to close connection between the contacts 127 and 128, an electromotive device actuated thereby remains in operation until the opposite solenoid for that armature is energized, thus opening the contacts. By variously combining the locking relays in this way 10 they can be actuated to operate the display devices in any desired manner or combination. Although only four jumpers or connectors 133 to 136 are shown, a plurality of jumpers are used 15 in actual practice to establish the desired circuit connections for any particular record.

As the present invention does not depend upon the specific structure of the phonograph repeater mechanism, the multiple contact rotary switches 20 or the locking relays it is believed unnecessary to illustrate or describe actual structures in any more detail, the drawings illustrating the necessary parts of the various elements and the circuit connections for operating them.

In operation the double pole switch 84, 84^a is 25 manually operated which closes the power circuits to the record repeater and the device is operated by the locking relays. Operation of the phonograph repeater rotates shaft 78 and its 30 cam 77 thereby separating contacts 80 and 81 and closing contacts 80 and 82. This completes a circuit through conductor 86 to one of the contacts 76 which is engaged by the pickup arm projection 73 held in open position when the tone arm is in its rest position. Movement of the tone 35 arm allows the contact 75 and 76 to make connection when the pickup arm reaches its playing position, thus closing a circuit connection through conductor 87 to one of the contacts 72. When the turntable cam 70 rotates the contacts 71 and 40 72 are intermittently opened and closed. Thus a circuit is closed to energize the solenoid 89 which is as follows: from battery 83 through 45 switch 84, conductor 85, contacts 80, 82, conductor 86, contacts 76 and 75, conductor 87, contacts 72 and 71, conductor 88 to one side of the winding 89 and thence by conductor 90 back to the other side of the battery 83.

A single impulse thus resulting from the closing of the contacts 71 and 72 for each partial 50 rotation of the phonograph record is imparted to armature 103 against spring 104 which causes pawl 102 to move the ratchet 101 of the switch 93 one step. Assuming that the brushes of all the 55 rotary switches are in their initial or open position as shown, the brushes 97 and 98 are advanced one step to contact number two for each brush. At this time a circuit is closed through brush 98 which may be traced as follows: From one side of the battery 83 by conductor 111 to brush 98, 60 contact number two of switch segments 96, conductor 110 to the solenoid winding 89 of switch 94, and thence through conductor 90 to the other side of the battery 83. This causes the actuation of the armature 103 of rotary switch mechanism 94 which actuates the rotary switches of switch 94 one step, but the switch mechanism 94 remains in its first step position while the switch mechanism 93 is actuated step by step for a complete 65 rotation of its contact brushes. The next time the brush 98 of the switch mechanism 93 engages its contact number two the switch mechanism 94 is actuated another step by its ratchet mechanism, and so on; thus a combination of different 70 circuit connections is made by the brushes 98

of the two switches 93 and 94, such that the number of possible different circuit connections depends upon the number of connected contacts or timing jacks 112 and 113, each of the contacts 96 of each switch being connected to jack plug terminals in the timing jacks 112 and 113. The contacts of the first switch are therefore shown connected to terminals 123—X and the contacts of the second switch are shown connected to the jack terminals L1, L2, L3—LX, depending upon 10 the number of contacts of each of the switches. 15

In operating the second locking relay, for example, the jumper terminal 133 connects the second contact of the plug terminal 112 and the relay contact 123 and the jumper 136 connects the relay contact 122 and the second switch terminal L5. Likewise jumper 134 connects the third contact of the plug terminal 112 and the relay terminal 124 whereas the jumper 135 connects the relay terminal 125 and the second switch 20 plug terminal L3.

When the rotary switches 93 and 94 are operated by their step by step movements to such an extent that the brush 98 engages the fourth contact and the brush 98 of the first switch engages 25 its fourth contact a circuit will be closed for energizing the second solenoid 121 as follows: From the battery 83 through conductor 111, brush 98, and contact number four of switch number one to terminal 3 of plug terminal 112, 30 thence by jumper 134 to contact 124, solenoid 120 to contact 125, jumper 135 to contact L3 of plug terminal 113 and thence through connected conductor to the fourth contact and brush 98 of switch number 2 and through a common return 35 conductor 140 to the other side of the battery 83. This will energize the double armature 126 of the second locking relay causing it to operate its movable contact 128 to closed connection with contact 127 and thereby to close an operating 40 circuit for any selected device which is connected to its terminals 131 and 132.

After the rotary switches have been similarly continued in a step by step movement for a predetermined time the brushes 98 will engage the 45 second and fifth contacts of switches 93 and 94 respectively, closing a similar restoring circuit through jumpers 133 and 136 to the terminals 123 and 122 of the restoring solenoid 120 which breaks the connection between the contacts 127 50 and 128.

Thus it is seen that each successive terminal of switch 94 engaged by its brush 98 closes a common return circuit for the momentarily excited segments connected with switch 93. For 55 each successive complete rotation of switch 93 a new common circuit is closed to the plug terminals L1, L2, etc., of switch 94 until the tone arm of the phonograph repeater reaches the end of play on the phonograph record. 60

When the record is completed an automatic cut-off action takes place and due to the rotation of the shaft 78 the tone arm 25 is raised and returned to its rest position, thereby separating the contacts 75 and 76 and thus stopping the movement of the rotary switches. At the same time the control cam 77 rotates to a position as shown in Fig. 2 where the contacts 80 and 82 are separated and 80 and 81 are closed. At this time all of the switch brushes are returned to their starting or open circuit position by the following resetting circuit: From one side of the battery 83, through switch 84, conductor 85, contacts 80 and 81, and a conductor 141 to the contacts 95 of switch 94, all of which are joined together by 75

common connectors except the rest or starting conductor number one, thence by a conductor 142 to the similarly connected conductors 95 of switch 93, and thence through the brushes 97 of both 5 rotary switches and conductors 109 through their contacts 108 and 107 and conductors 110 and 88 to their respective solenoid windings 89 and thence by a common return wire 90 to the other side of the battery 83. Energizing the 10 solenoids causes intermittent vibrating movement of the armatures 103, alternately making and breaking the connections between contacts 107 and 108. Thus the brushes 97 of both switches are rapidly rotated in a step by step manner 15 until they come to rest on the number one or open segment number one of each switch which is the starting position for a repetition of the cycle.

As the manual switch 84—84^a remains closed 20 the phonograph repeater will again commence to operate and the cycle of operations will be repeated. In this way robot displays combining movements of various parts with a talking record can be continued and repeated without manual attention. The external operating circuits 25 when once established are not disturbed and the resetting movement of the switches moves the common circuit brush off of the last movement segment of the segment rotary switch.

30 Although in the operation of the locking relay only a single locking and unlocking operation is described, it will be understood that in the operation of an actual installation there will be as many multiple jack connections as there are different changes in the desired operation of the device. In an actual installation the jumper or jack connections are often so numerous as to produce a maze of connections, a number of them connected to each of the available plug terminals 40 but timed by their connection with the different terminals so that they will be operated in properly timed relation to the record itself. Thus any desired operation of the devices is obtained and any device may be operated as long or as frequently as desired.

45 Among the advantages of the invention are the portability and compactness of the equipment; the possibility of using sound records of different diameters, pitches, velocities, and different types of records; the use of jack panels and quick detachable jumpers to facilitate timing; the use of an electro-magnetic counter for visually locating the impulse corresponding to the recorded sound sequences to be synchronized; 50 the method of holding energized external display circuits a predetermined time and the possibility of adding additional rotary switches for complex external display circuits; and the method of obtaining complete automatic operation and automatically resetting the rotary switches to starting 55 position.

We claim:

1. An electric robophone comprising a phonograph, a pair of rotary multiple contact switches, 60 electro-responsive means for operating the switches step by step, rotary contact means carried by the phonograph for energizing the electro-responsive means a number of times as a record is played, and circuit means for making the 65 electro-responsive means of one switch dependent upon the step by step movement of the preceding switch.

2. In an electric robophone, a phonograph, a 70 plurality of rotary multiple contact switches, 75 electro-responsive means for operating the

switches step by step, turntable switch mechanism carried by the phonograph for energizing the electro-responsive means one or more times for each rotation as the record is rotated, and circuit closing means for making the electro-responsive means of each succeeding switch dependent upon the step by step movement of the next preceding switch. 5

3. The combination with a phonograph, of a plurality of rotary multiple contact switches, 10 electro-responsive means for operating each switch step by step, turntable cam switch mechanism in connection with the phonograph operated upon each rotation thereof for energizing the electro-responsive means to rotate one switch 15 step by step for one complete rotation before the electro-responsive means of the next switch is energized to move it for each step.

4. In an electric robophone, a phonograph having a turntable cam switch operated by the rotations thereof, a plurality of rotary switches, an electro-responsive means for operating each switch step by step, means on each switch to close a circuit to the electro-responsive means of the next switch after the first switch has moved a 25 complete rotation in one direction, and means for quickly restoring all switches to starting position when the playing of a record is finished.

5. In an electric robophone, a phonograph having a rotatable contact closer, the contact closer 30 being operated upon each rotation of the phonograph, a plurality of electric switches actuated by said closer, an electro-responsive step by step mechanism for each switch, means for insuring that each switch is moved one complete rotation 35 before the next switch is advanced one step, and conductors for closing energizing circuits in timed relation with the phonograph when contacts of two switches are simultaneously engaged.

6. In an electric robophone, a phonograph having a rotatable contact closer, the contact closer being operated upon each rotation of the phonograph, a pair of rotary multiple contact switches actuated by said closer each having means for separately engaging the contacts, electro-responsive means actuated by the phonograph for operating the said means of each switch step by step, conductors connected to each of the contacts of each switch, and multiple jack connections for the contacts to actuate electro-responsive devices, the said connections closing a circuit through corresponding contacts of adjacent switches in timed relation to the phonograph. 45

7. An electric robophone for operating a number of external electro-responsive devices, comprising a phonograph having a rotatable contact closer, the contact closer being operated upon each rotation of the phonograph, a plurality of rotary multiple contact switches actuated by said closer, means actuated by the phonograph for actuating the switches step by step, jack terminal connections for each of the contacts of each switch, and detachable jumper connections from the terminal contacts to the electro-responsive devices whereby the said device is operated in 55 timed relation with the phonograph when the switch contacts corresponding thereto are closed by the step by step movement of the switches. 60

8. In an electric robophone for operating electro-responsive devices, a phonograph having a 70 rotatable contact closer, the contact closer being operated upon each rotation of the phonograph, a plurality of rotary multiple contact switches actuated by said closer, terminal plug-in connections for the contacts of each switch, means in 75

connection with the phonograph for actuating each switch separately step by step, means for rotating one switch a predetermined amount before the next switch is operated, jumper connections for each switch to a device to be operated, the two switches being required to provide a return circuit for energizing one of the electro-responsive devices in timed relation to the phonograph depending upon the contacts which are engaged.

9. In an electric robophone for actuating electro-responsive devices, a phonograph, rotary multiple contact switches, means comprising a rotary circuit closer controlled by the phonograph for actuating each switch step by step and each succeeding switch being dependent upon a predetermined step by step movement of the next preceding switch, plug-in terminals for each separate contact of each switch, detachable jumper jacks for connecting each contact with one terminal of one electro-responsive device to be operated, and means for visually timing the impulse of the phonograph corresponding to which the operation of the electro-responsive device is to be synchronized by the jumper connection to the switches.

10. In an electric robophone for operating electro-responsive devices, rotary multiple contact switches, means comprising a rotary circuit closer controlled by the phonograph for actuating the switches step by step, means for connecting the contacts of the switches to the devices to be operated in timed relation, and counter means for visually indicating the step by step impulse corresponding to which the switch connections are made for operating the electro-responsive device.

11. In an electric robophone, a phonograph, rotary multiple contact switches, means comprising a rotary circuit closer controlled by the phonograph and operated at each rotation thereof for operating the switches step by step, and switch means to limit the step by step movement to the actual time that the phonograph is in playing position.

12. In an electric robophone, a phonograph having a tone arm for playing a record, rotary multiple contact switches, means controlled by the operation of the phonograph due to the rotations thereof for operating the switches step by step, and electric switch means operated by the tone arm for closing a circuit to the switch operating means only when the tone arm is in record playing position.

13. In an electric robophone, a phonograph, a pair of rotary multiple contact switches each having an electro-responsive mechanism for moving it step by step in one direction, rotary circuit closing means comprising a rotary circuit closer in connection with the phonograph and operative at each rotation thereof for energizing the step by step mechanism of the first switch, and a circuit closed by one switch at each operation thereof for energizing the step by step operating device of the next switch.

14. In an electric robophone, a phonograph, rotary multiple contact switches each having a plurality of sets of contacts and an electro-responsive device for actuating it step by step, means comprising a mechanical circuit closed in connection with the phonograph operative at each rotation thereof for actuating the electro-responsive devices of the switches, and means in connection with the electro-responsive device of each switch for quickly actuating the electro-responsive device independent of the phonograph.

graph actuation thereof for restoring the switch to starting position.

15. In an electric robophone, a phonograph, rotary multiple contact switches each having an electro-responsive device for actuating it step by step, means comprising a rotary mechanical circuit closed in connection with the phonograph operative at each rotation thereof for energizing the electro-responsive devices to operate the switches step by step and successively for regular timed operation, means in connection with the phonograph tone arm for insuring regular operation of the electro-responsive devices only when the record is being played, and an intermittent make and break connection established when the phonograph record has been played for actuating the electro-responsive devices to return the switches quickly to starting position independently of the phonograph means for controlling said electro-responsive devices.

16. In an electric robophone, a repeating phonograph, rotary multiple contact switches having an electro-responsive step by step device for each switch, means comprising a rotary mechanical circuit closed in connection with the phonograph operative at each rotation thereof for actuating the step by step devices for playing a complete record, timed means in connection with the phonograph for closing a circuit to the electro-responsive devices through the phonograph operated means for the regular step by step movement of the switches, and a circuit connection also closed by the said timing means when the playing of a record is complete for quickly actuating the step by step devices for returning the switches to starting position.

17. In an electric robophone, a repeating phonograph, rotary multiple contact switches each having an electro-responsive step by step rotating device, means comprising a rotary mechanical circuit closed in connection with the phonograph operative at each rotation thereof for closing a circuit to energize the electro-responsive devices in timed relation to a record being played, a timed cam for making a complete rotation for one operation of the phonograph record, and circuit means including a switch in connection with the cam for closing the said circuit controlled by the phonograph while the record is being played and for opening the said circuit as soon as the record playing is finished, and also for closing another circuit to the electro-responsive devices for the switches for quickly operating them to return the switches to starting position in a step by step movement.

18. In an electric robophone, a repeating phonograph, rotary multiple contact switches and an electro-responsive device for actuating each switch in a step by step movement, means comprising a rotary mechanical circuit closed in connection with the phonograph operative at each rotation thereof for actuating the electro-responsive devices to operate the switches in a timed step by step relation with respect to a record being played, and means also in connection with the phonograph for actuating the electro-responsive devices quickly in a step by step movement after the playing of the record is completed.

19. In an electric robophone, a phonograph, a pair of rotary multiple contact switches, an electro-responsive device in connection with each switch for operating it in a step by step movement, means comprising a rotary mechanical circuit closer in connection with the phonograph

operative at each rotation thereof for moving one switch a complete rotation before the other switch is moved one step and in timed relation to the playing of the phonograph, and means operated by the phonograph when the playing of a record is complete for operating both electro-responsive devices in unison for returning their switches to starting position.

20. In an electric robophone, a phonograph having a cam switch rotatable with the record dial, a tone arm for separating the switch contacts during the playing movement of the arm, and a rotatable cam shaft for opening one switch and closing another; a pair of rotary multiple contact switches, each having an electro-responsive step by step ratchet mechanism; circuit means in connection with the phonograph

switches and one of the electro-responsive devices for connecting them in series during the timed rotation of the phonograph as determined by the movement of the tone arm, and circuit closing means in connection with the contacts of one of the switches and the electro-responsive device of the other for closing an energizing circuit for the electro-responsive device of the said other switch, and circuit closing means in connection with both rotary switches and with the cam switch of the phonograph for closing circuits simultaneously to the electro-responsive device of both switches when the playing of a record is completed. 5 10 15
